CHRISTMAS TREE HOLDER

Joseph Haumann, Chicago, Ill., assignor to
Henry Hildebrandt, Chicago, Ill.

Application March 8, 1947, Serial No. 733,284

4 Claims. (Cl. 248—44)

1

This invention relates to Christmas tree holders.

The principal object of this invention is to provide an improved Christmas tree holder wherein the tree is automatically centered and held upright, wherein the tree may be watered, wherein few parts are utilized for accomplishing these results, wherein the holder may be inexpensively and readily manufactured, and wherein in certain ornamental characteristics are provided.

In accordance with this object of the invention, the Christmas tree holder may include a container substantially triangular in cross section adapted to contain water, gripping levers in the container and pivoted intermediate their ends to the corners of the triangular container and a conical member in the container between the gripping levers and guided by the side walls of the container for receiving the end of the tree and engaging the lower ends of the gripping levers for forcing the upper ends thereof into engagement with the trunk of the tree. A spring may also be utilized for urging the conical member upwardly. The container may also be provided with hollow supporting legs provided with ornamental openings, and lights in the legs may illuminate the openings.

Further objects of this invention reside in the details of construction of the component parts and the cooperation between the same.

Other objects and advantages will become apparent to those skilled in the art upon reference to the accompanying specification, claims, and drawing in which—

Figure 1 is top plan view, partly in section, of the Christmas tree holder;

Figure 2 is a vertical sectional view through the holder taken substantially along the line 2—2 of Fig. 1;

Figure 3 is a partial side elevational view looking from the left of Fig. 2 as indicated by the line 3—3 of Fig. 2.

The Christmas tree holder includes a container having side walls 10 arranged in triangular formation and a bottom wall 11 provided with a flange 12 for fitting over the side walls 10. In the formation of the side walls 10 and the bottom wall 11, the joints are preferably made watertight so that the container is adapted to hold water for watering the tree placed therein.

Provided at each corner of the container are brackets 13 which are generally U-shaped in cross section. The upper edges of the brackets 13 are provided with lips 14 for properly locating

the brackets 13 in the corners of the triangular container. Each of the brackets 13 is adapted to carry a gripping lever 15 which also is generally U-shaped in cross section. The upper end of each gripping lever 15 is flared at 16 to provide gripping jaws, and these gripping jaws may be provided with serrations 17. The lower ends 18 of the gripping levers 15 are bent inwardly. Each of the levers 15 is provided intermediate its ends with holes adapted to receive pivot pins 19 extending through corresponding holes in the brackets 13. In this way, the levers 15 are pivotally mounted on the brackets 13. When the brackets 13 are located in the corners of the triangular container with the assistance of the lips 14, they may be secured in place in the corners by spot welding, brazing, or the like as indicated at 20.

Located in the container and between the levers 15 is a conical member 22 provided with an opening 23 at the bottom thereof. The opening 23 is adapted to receive ears 24 formed on a plate 25 so that the conical member 22 is secured to the plate 25. The upper end of the conical member 22 is guided in the triangular container by the side walls 10 of the container, and the lower end of the conical member 22 is guided by the plate 25 coating with the side walls of the container. A spring 27 is interposed between the bottom wall 11 of the container and the plate 25 for normally urging the plate 25 and hence the conical member 22 upwardly.

In assembling the Christmas tree holder, the triangular container is first formed, the spring 27 is inserted therein, and then the plate 25, conical member 22, gripping levers 15, and the brackets 13 are inserted in the container. Prior to the insertion of the brackets 13 and the gripping levers 15, they are pivoted together by the pivot pins 19. After the parts are thus assembled, the brackets 13 are secured to the corners of the triangular container, and the side walls of the container operate to maintain the pivot pins 19 in place.

It will be noted from Fig. 2 that the angle of inclination of the lower ends of the gripping levers 15 is greater than the angle of inclination of the conical member 22. Thus, as the conical member 22 is moved downwardly, the lower ends of the gripping levers 15 are moved outwardly to cause the upward ends thereof to move inwardly. Because of the difference in angular inclination, a powerful camming action on the gripping levers by the conical member is provided.

When a Christmas tree having a trunk as indi-

cated at 26 is inserted in the container, the end of the trunk engages in the conical member 22 and the weight of the tree moves the same downwardly against the action of the spring 27. The conical member 22 acts against the lower ends of the gripping levers 15 to force the upper ends thereof into engagement with the trunk of the tree. The upper ends of the gripping levers 15 thus firmly grip the tree trunk and automatically center the tree and hold it upright. The heavier the tree, the greater is the force applied by the gripping levers 15. When the tree is thus inserted and held in the holder, the container may be filled with water for watering the tree. When it is desired to remove the tree, all that is necessary is to pull the tree out of the container, and in so doing, the conical member 22 moves upwardly to release the gripping levers 15 so that the tree may be readily removed.

The flange 12 of the bottom wall 11 of the container is provided with slotted ears 30 by which hollow supporting legs 31 are secured to the container. The hollow supporting legs are preferably formed from sheet metal and are provided with inturned portions 32 to form pedestals and inturned portions 33 for strengthening purposes. The sides of the hollow legs 31 may be provided with ornamental openings 34, and the sides of the legs also are provided with hooked ears 35 adapted to be received in the slotted ears 30. In assembling the hollow legs 31 on the container, the hooked ears 35 are inserted in the slotted ears 30 and then the legs are pivoted upwardly about the hooked ears 35 until the upper portions thereof engage the corners of the container at 36. The weight of the container and the tree carried thereby operates to hold the legs 31 in place on the container. Thus, a sturdy leg construction is provided.

The reinforcing flanges 33 may carry clips 38 which in turn carry lights indicated at 39, which lights operate to illuminate the ornamental openings 34, thus adding to the ornamental characteristics of the holder.

While for purposes of illustration one form of this invention has been disclosed, other forms thereof may become apparent to those skilled in the art upon reference to this disclosure and, therefore, this invention is to be limited only by the scope of the appended claims and the prior art.

I claim for my invention:

1. A Christmas tree holder comprising a container substantially triangular in cross section adapted to contain water, gripping levers in the container and pivoted intermediate their ends to the corners of the triangular container, a conical member in the container between the gripping levers and guided by the side walls of the container for receiving the end of the tree and engaging the lower ends of the gripping levers for forcing the upper ends thereof into engagement with the trunk of the tree.

tainer for receiving the end of the tree and engaging the lower ends of the gripping levers for forcing the upper ends thereof into engagement with the trunk of the tree.

5. A Christmas tree holder comprising a container substantially triangular in cross section adapted to contain water, gripping levers in the container and pivoted intermediate their ends to the corners of the triangular container, a conical member in the container between the gripping levers for receiving the end of the tree and engaging the lower ends of the levers for forcing the upper ends thereof into engagement with the trunk of the tree, the upper end of the conical member being guided by the side walls of the container, and a plate secured to the lower end of the conical member and engaging the side walls of the container for guiding the lower end of the conical member.

20. 3. A Christmas tree holder comprising a container substantially triangular in cross section adapted to contain water, three gripping levers, three brackets, one for each lever, pivot pins for pivotally mounting the levers intermediate their ends to the brackets, means for securing the brackets in the corners of the triangular container with the side walls of the container holding the pivot pins in place, and a conical member in the container between the gripping levers and guided by the side walls of the container for receiving the end of the tree and engaging the lower ends of the gripping levers for forcing the upper ends thereof into engagement with the trunk of the tree.

35. 4. A Christmas tree holder comprising a container substantially triangular in cross section, slotted ears on the sides of the container adjacent the bottom, and three hollow legs partially overlying the corners of the container and engaging the corners of the container above the bottom and each having a pair of hooked ears engaging in the slotted ears.

JOSEPH HAUMANN.
